CLAIM

The ornamental design for a light and front hood for an automobile, as shown and described.

DESCRIPTION

FIG. 1 is a front perspective view of a light and front hood for an automobile, of the new design, with the light and front hood located in a closed position;

FIG. 2 is a front perspective view thereof;

FIG. 3 is a top view thereof;

FIG. 4 is a front view thereof;

FIG. 5 is a side view thereof;

FIG. 6 is a side view thereof, opposite that of FIG. 5;

FIG. 7 is a bottom view thereof;

FIG. 8 is a rear view thereof;

FIG. 9 is a side view thereof, with the light and front hood located in the closed position;

FIG. 10 is a side view thereof, with the light and front hood located in an open position; and,

FIG. 11 is a front perspective view thereof, with the light and front hood located in the open position.

The broken lines (including for example, the lower portion of the front hood below the light, the wheels, the front fascia, the windshield, and the text "LUCID") are for illustrative purposes only and form no part of the claimed design. The dashed lines in FIGS. 7 and 8 indicate that the portions of the light and front hood internal to the periphery are not part of the claimed design. The stippling area at the front of the hood indicates the light portion of the claimed design.

1 Claim, 10 Drawing Sheets
